UNITED STATES PATENT OFFICE.

CHARLES W. SANBORN, OF ST. LOUIS, MISSOURI; WILLIAM W. SANBORN, ADMINISTRATOR OF SAID CHARLES W. SANBORN, DECEASED, ASSIGNOR TO STANDARD HEEL AND COUNTER COMPANY, OF ST. LOUIS, MISSOURI, A CORPORATION OF MISSOURI.

FLOOR MAT.

Application filed October 27, 1922. Serial No. 597,230.

This invention relates to floor mats, and more particularly to such mats as are made up of a series of connected links forming a flexible mat which can be rolled up.

Such mats are usually constructed of a series of links arranged in rows, the links in each row alternating with those in adjacent rows and the various rows being connected by a series of pintle rods passing through the links. Such a construction usually leaves along the side edges of the mat a succession of links and spaces. This is an objectionable form for the edge of a mat since it leaves projecting portions which are liable to catch in obstructions or to be caught by the feet of persons walking over the mat with consequent danger of causing accidents.

One of the objects of this invention, therefore, is to provide such a link constructed mat which shall have a substantially continuous side edge.

Another object of this invention is to provide such a mat having an edge free from prominent projections.

Further objects will appear from the detail description taken in connection with the accompanying drawing, in which:

Figure 1 is a plan view illustrating a mat embodying this invention; and

Figure 2 is a side edge view of Figure 1.

Referring to the accompanying drawing, the mat is constructed of a series of links 1 arranged in alternate rows, the links of successive rows alternating with each other.

The successive rows of links are connected by a series of pintle rods 2, each passing through the ends of the links of two adjacent rows. These pintle rods may be constructed of stout wire bent into a U-form,

each such U forming two pintle rods. After passing the rods through the ends of the links, their free ends 3 may be bent over against the last link and joined together by a suitable connector 4 so as to prevent their working loose.

Before bending over the ends of the pintle rods, the links may be subjected to an edgewise pressure directed along the pintle rods so as to hold the links firmly together under pressure. In this way, after the ends 3 are bent over and fastened, the links will be held firmly together under considerable pressure. This is desirable since

each link is constructed of a series of laminas 5 punched or otherwise suitably formed from leather or other suitable material.

55

In order to stiffen the ends of the mat and to prevent the same from curling up, such ends may be formed of a series of standard links 1 alternating with special links 6 adapted to engage three pintle rods as illustrated in Figure 1. These extended links 6 together with the alternate links 1 along the ends of the mat provide a continuous and uniform end and a stiff section along the end so as to prevent curling of the mat at that point. A similar stiffening row of links may be placed at any point in the body of the mat so as to reenforce and stiffen the same. Such an arrangement is illustrated at the lower portion of Figure 1 where a row is formed of two sets of links 6 alternately projecting from the row in opposite directions.

60

65

70

Along the side edges of the mat and between the links 1 a series of laminated blocks 7 is provided. These blocks are formed of punched laminations in a manner similar to the formation of the links themselves. Each block consists of a series of such laminations mounted between successive links along the side edge of the mat and fastened to the links of the adjacent rows by means of a suitable fastener 8. These links are formed with hollowed ends 9 adapted to fit the ends of the links 1 but to 85 allow for rotation of the links therein so as to allow for rolling up of the mat. The blocks 7 are substantially flush with the links 1 along the side edge of the mat and provide, therefore, a substantially uniform edge 90 along each side of the mat.

80

This invention provides, therefore, a durable mat of cheap construction which presents continuous end and side edges and is adapted to roll up when not in use. The 95 end construction formed of alternating links 1 and 6 provides a stiff end adapted to lie flat while the blocks 7 interposed between successive links 1 along the side edges of the mat provide substantially continuous side 100 edges, so as to avoid all danger of projections catching in obstructions. Forming the links of leather suitably corrugated as illustrated in Figure 2 provides a very du-

rable wearing surface and one presenting a good purchase for the feet.

It is obvious that various changes may be made in details without departing from the spirit of this invention; it is, therefore, to be understood that this invention is not to be limited to the specific details shown and described.

Having thus described the invention, what is claimed is:

1. A floor mat comprising, a series of connected links arranged in rows with the links of adjoining rows alternating, and blocks adapted to fill the spaces between the links of alternate rows along the side of the mat.
2. A floor mat comprising, a series of connected links arranged in rows with the links

of adjoining rows alternating, and blocks attached to the links of alternate rows along the side of the mat adapted to fill the spaces between the links connected thereto.

3. A floor mat comprising, a series of links arranged in rows with the links of adjoining rows alternating, a series of pintle rods joining said links to form a flexible chain-like structure, and filler blocks between the links of alternate rows along the side of the mat, the links of an inside row being extended so as to receive the pintle rods of the end row, and certain of said extended links carrying such filler blocks.

In testimony whereof I affix my signature this 2nd day of Sept., 1922.

CHARLES W. SANBORN.
